Attorneys.

UNITED STATES PATENT OFFICE.

JULIUS E. LILIENFELD, OF KEW GARDENS, NEW YORK.

HIGH-VACUUM DEVICE FOR INFLUENCING CURRENTS.

Application filed September 3, 1921. Serial No. 498,391.

To all whom it may concern:

Be it known that I, JULIUS E. LILIENFELD, a citizen of Poland, residing at Kew Gardens, in the county of Queens and State of New York, have invented certain new and useful Improvements in High-Vacuum Devices for Influencing Currents (for which I have filed applications in Germany, Feb. 5, 1920, and Germany, Feb. 9, 1921), of which 10 the following is a specification.

This invention relates to high vacuum tubes and more particularly to devices of this character for influencing electric currents.

15 It is the object of the invention to produce a simple and efficient device of the type used for setting up oscillations and it is a particular object to provide simple and highly efficient high vacuum devices for use as transmitters and amplifiers in radio work.

The principle of operation is based upon the discovery that an intense discharge can be started in an extremely high vacuum between cold electrodes if the cathode is provided with surfaces of small curvature and if these surface or surfaces are sufficiently close to an anodic surface. Provided that the electrodes are made of a highly refractory material, that they have been freed of 25 the occluded gases by heating, preferably by means of an electronic bombardment, and that further the vacuum is sufficiently high, no ionization and no discharge between the electrodes will take place. Consequently no 30 deterioration of the cathodically active surface occurs and the operation of the tube is uniform and constant. Incidents such as the burning through of the wires of the hot cathode tubes are eliminated and because of the 35 absence of a heating circuit a material simplification of the apparatus is obtained.

The voltage required is a function of the geometrical arrangement of the electrodes. It increases in proportion to the distance between the electrodes and the radius of curvature of the cathodic active surface or surfaces as the case may be. In order to make 45 it possible to operate with a relatively low voltage the electrodes must be placed very close together and the cathode must be provided with a large number of very thin and very sharp points.

In order to utilize the discharge for the particular purpose referred to, the tube must 50 contain in addition to the cathodic active

surface and the anodic surface placed close to the former one or more other electrodes.

Some of these additional electrodes may be provided in order to receive the flow of electrons originated by the discharge between the anode and the cathode, while other additional electrodes may be loaded to different potentials and thereby be employed to change either the discharge between the anode and the cathode or the flow of electrons to other electrodes. 60 65

For a full understanding of the invention reference is had to the accompanying drawings in which—

Fig. 1 is a diagrammatic representation of 70 one form embodying the invention;

Fig. 2 shows a modification thereof;

Fig. 3 is a diagrammatic representation of a different arrangement for carrying out 75 the invention;

Fig. 4 is a diagrammatic view showing a modification of the form shown in Fig. 3;

Figs. 5 and 6 are fragmentary sectional views of detail involving a modification of the forms of electrodes indicated in Figs. 1 80 and 2.

Fig. 7 is a fragmentary sectional view of detail involving a modification of the forms of electrodes indicated in Fig. 3; and

Fig. 8 is a diagrammatic view of an arrangement of electrodes involving another modification of Fig. 1. 85

All forms disclosed include, aside from the usual electrodes, an auxiliary anode in correlation therewith, a simple arrangement 90 being shown in Figs. 3 and 4.

In Fig. 3, K indicates the cathode and A₁ and A₂ are the anodes. D represents a dynamo having one pole connected to the cathode and energizing the anodes through 95 branch circuits including the inductances L and L₁, the capacities C and C₁ and the auxiliary inductance L₂. By means of a switch S the branch circuit L₂, C₁, L₁ and anode A₂ may be disconnected from the 100 dynamo and the branch circuit leading to the anode A₁.

While the switch S is open, simply a non-oscillatory discharge will pass between K and A₁. When the switch is closed, the 105 anode A₂ comes into play and oscillations are started by the inductive interaction of coil L on coil L₂ in the circuits C, L and C₁, L₁. The circuits containing L and L₂ must be tuned to a corresponding frequency, while 110

those containing L and L_1 may be in such condition of tuning and phase that the oscillations generated in both may be superposed at a certain antenna.

- 5 In Fig. 4 one pole of the dynamo D_1 is connected to the cathode K_1 through the inductance L_2 and to the anode A_4 through a resistance R_1 and an inductance L_4 . The other pole of the dynamo is connected to the 10 anode A_3 through a resistance R_2 , an inductance L_5 and a switch P . The anodes A_3 and A_4 are interconnected through a resistance R_3 , a condenser C_2 and an inductance L_6 in series relation. The branch 15 $P_3 C_2 L_6$ is the oscillatory circuit proper, as is obvious.

In the arrangement shown in Figs. 3 and 4 the electrons flow directly to the anodes. However, there are other ways of utilizing 20 the electronic discharge for the purposes of the invention, as for instance illustrated in Figs. 1 and 2.

The arrangement shown in Figs. 1 and 2 is based on two observations: (1) That at 25 the points of impact of the electrons on the anode a new flow of electrons—reflected and secondary—is started, (2) That the electrons coming from the active cathodic surfaces are accelerated in such close proximity to these 30 surfaces that thereafter they are not necessarily driven by the field to the nearest part of the anode, but may as likely travel longer paths to more distant anodic surfaces.

The cathodically active surfaces of the 35 electrode K_2 are placed close to the anodic electrode H while A_5 is the anode which receives the combined flow of primary and secondary electrons of the system $K_2 H$.

One pole of the dynamo D_2 is connected 40 to the cathode while from the other pole through the oscillating circuit including the capacity C_3 and inductance L_7 a charge is impressed on the anode A_5 . Coil L_7 is inductively coupled with L_8 and therefore an 45 oscillating potential is impressed upon the anode H producing an oscillatory flow of electrons in the tube, provided that the circuits containing coil L_7 and coil L_8 , respectively, are tuned to a corresponding frequency.

Another way of energizing the device 50 shown in Fig. 1 can be based on the fact that while $K_2 H$ is energized and A_5 kept on different negative voltages, the higher 55 the negative voltage of A_5 , the less the current flowing to this electrode. This negative characteristic of the discharge flowing to A_5 may be used for the production of oscillations in a circuit similar to the Poulson 60 arc.

By similar means well known in the art an amplifying circuit can be set into operation.

The device illustrated in Fig. 2 differs 65 from that of Fig. 1 principally only by the

interposition of a grid G between the auxiliary anode H_1 and the anode A_6 . This grid acts upon the electronic stream originated in the system $K_3 H_1$ according to its potential and permits a larger or smaller part of the stream to strike on A_6 so that in this way oscillations will be produced. 70

In this case the oscillating potential produced by the inductive action of coil L_9 upon coil L_{10} is imparted to the grid G and 75 therefrom the oscillations of the discharge in the tube are originated, provided that the circuits of L_9 and L_{10} are tuned as indicated above.

The dynamo D_3 is connected to the cathode 80 K_3 and the auxiliary anode H_1 and causes the release of electrons from the system $K_3 H_1$ while the dynamo D_4 is instrumental in relaying the electrons thus liberated to the anode A_6 . $L_9 C_4$ represent the oscillatory 85 circuit and L_{10} the inductance which impresses upon the grid G the voltage which governs the electronic stream to A_6 .

While I have shown two separate dynamos, it is of course possible, as is well understood, to use a single dynamo having its poles interconnected by a resistor for establishing any desired point of potential between the potentials of the opposite poles. 90

In order to increase the active cathodic 95 surface and make the devices symmetrical and easier to operate the constructions so far described may be modified in various ways.

Instead of the arrangement shown in Fig. 1 a tube may be constructed with concentric 100 electrodes. Thus, as shown in Fig. 5 the cathode K_4 may be surrounded by the auxiliary anode H_2 and this system in turn may be surrounded by the anode A_7 .

Similarly, as shown in Fig. 6, the concentric arrangement including the cathode K_5 , the auxiliary anode H_3 , the grid G_1 and the anode A_8 may replace the arrangement shown in Fig. 2.

Again the form and disposition of the electrodes according to Figs. 3 and 4 may be modified according to the disclosure in Fig. 7. The cathode K_6 has the form of a disk and is surrounded by two rings A_9 and A_{10} 115 constituting the anodes.

As indicated in Fig. 8 which represents an arrangement such as shown in Figs. 1 and 5, the cathode may comprise a plurality of disks K_7 in parallel relation and the auxiliary anode may similarly comprise a plurality of annular disks H_5 preferably in alignment with the disks K_7 and concentrically disposed thereto, while the anode may be a cylindrical tube A_{11} concentrically 120 disposed about the anode elements. 125

There are, of course, other changes and modifications of which the electrodes and their mutual relationship are susceptible. Thus while I have indicated in Figs. 5, 6 and 7 the cathodes as innermost in the ar- 130

angement, the relative positions of the electrodes may be readily reversed.

For the purpose of reducing the voltage required to energize the tubes, cathodes having a relatively large number of sharp points p may be used as indicated for the sake of illustration in Fig. 5. Such cathodes may be advantageously formed by clamping a thin sheet of metal indented on its outer 10 edge or a large number of very thin pieces of wire between two flat metal rods. The smaller the distance of the discharge points of the cathode from the anodic surface, the smaller the voltage required to induce a discharge.

In connection with such small inter-electrodes distances it is advisable to dispose the stems supporting the electrodes in planes substantially at right angle to the direction 20 of the gap or the discharge so that the expansion due to changes of temperature may be practically without effect on the size of the gap.

In the foregoing I have referred only to 25 arrangements in which single electrodes were used. Within the scope of the invention it is of course possible to use multiple electrodes. Thus for the sake of example the arrangement generally represented by Fig. 30 1 and modified according to Fig. 4 may include a plurality of superposed disks K_7 , a like plurality of rings H_5 and a tube section A_{11} , constituting the cathode, the auxiliary anode and the anode respectively.

To obtain a sufficient vacuum, not only the anode, but also the cathodes must be bombarded during the evacuation by an electronic stream.

For this purpose either special cathodes 40 with active surfaces may be provided or such surfaces may be mounted on the anode so that upon inverting the current electrons are released in the direction of the cathode which electrons bombard the latter thereby 45 heating it up and expelling all occluded gases.

Arrangements for this purpose are described in my application Serial No. 498,392 filed Sept. 3, 1921.

50 I claim:

1. Apparatus of the character described, comprising an envelope evacuated to such a degree that ionization is substantially prevented, electrodes including an unheated 55 cathode having an active surface or surfaces of small radius of curvature in close proximity to an anode for producing an electronic discharge and means for producing a separate field of force to modify the character of the discharge.

2. Apparatus of the character described, comprising an envelope evacuated to such a degree that ionization is substantially prevented, an unheated cathode having active 65 surfaces of small radius of curvature, a

plurality of anodes in close proximity to said surfaces for producing an electronic discharge and means for influencing at will the discharge to selectively pass to one or the other of said anodes.

3. Apparatus of the character described, comprising an envelope evacuated to such a degree that ionization is substantially prevented, an unheated cathode having a surface of small curvature, an anode in close proximity to said surface, a second anode, means for discharging a stream of electrons from the cathode and means including the second anode for modifying said stream.

4. Apparatus of the character described, comprising an envelope evacuated to such a degree that ionization is substantially prevented, an unheated cathode having a surface of small radius of curvature, an anode in close proximity to the said surface, a second anode, means including the cathode and the first anode for producing a non-oscillatory discharge and means including the second anode for producing an oscillatory discharge.

5. Apparatus of the character described, comprising an envelope evacuated to such a degree that ionization is substantially prevented, an unheated cathode having a surface of small radius of curvature, an anode in close proximity to the said surface, means for releasing a stream of electrons from the cathode, another anode and means for directing the primary electrons emitted from the cathode together with the secondary electrons released due to the impact of the primary electrons upon the first anode, to the additional anode.

6. Apparatus according to claim 5 including means for modifying the character of the electronic discharge between the first anode and the other anode.

7. Apparatus according to claim 5 including means for modifying the character of the electronic discharge between the first anode and the other anode, the said modifying means including a grid between the first anode and the additional anode.

8. Apparatus of the character described, comprising an envelope evacuated to such a degree that ionization is substantially prevented, an unheated cathode having a surface of small radius of curvature, an anode in close proximity to said surface, means for releasing a stream of electrons from the cathode, a plurality of additional anodes and means for acting upon the additional anodes to direct the primary electrons emitted from the cathode together with the secondary electrons released from the first anode upon the additional anodes.

9. Apparatus according to claim 8 in which one of the additional anodes has the shape of a grid.

10. Apparatus of the character described,

comprising an envelope evacuated to such a degree that ionization is substantially prevented, an unheated cathode, a plurality of anodes disposed in substantially the same direction at different distances from the cathode and means for differently acting upon the cathode and the anodes to impress different charges upon the latter.

11. In a high vacuum device, the combina-

tion of a tube evacuated to such a degree ¹⁰ that ionization is substantially prevented and electrodes therein including an unheated cathode having a relatively large number of sharp points extending into close proximity to an anodic surface. ¹⁵

In testimony whereof, I affix my signature.

JULIUS E. LILIENFELD.
